GUSTAV O. BRANDT AND THOMAS MAHONEY, OF DETROIT, MICHIGAN, ASSIGNORS TO
LEONARD A. YOUNG, OF HIGHLAND PARK, MICHIGAN.

CUSHION-SPRING.

1,257,310.

Specification of Letters Patent. Patented Feb. 26, 1918.

Application filed March 26, 1917. Serial No. 157,354.

To all whom it may concern:

Be it known that we, GUSTAV O. BRANDT and THOMAS MAHONEY, citizens of the United States, residing at Detroit, county 5 of Wayne, State of Michigan, have invented a certain new and useful Improvement in Cushion-Springs, and declare the following to be a full, clear, and exact description of the same, such as will enable others skilled 10 in the art to which it pertains to make and use the same, reference being had to the accompanying drawings, which form a part of this specification.

This invention relates to cushion springs 15 in which the supporting springs are tied together by what is believed to be a new and useful connecting element. This connecting element is characterized by holding the springs in erect uniformly spaced positions but capable of allowing them to approach or draw away from one another when subjected to stresses.

In the drawings,—

Figure 1 is a plan view.

Fig. 2 is a section on the line A—A of Fig. 1.

Fig. 3 is an enlarged section detailing the tying members.

Fig. 4 is an enlarged detail showing the locking at the intersecting of two ties.

The usual hour-glass springs are designated *a*; the border wire *b*. Along the front edge of the border wire is a reinforcing bar *c* clipped to the border wire by turned-over 35 ends *d* and the bands *e* which pass through slots *f* in the strip *c*. The purpose of this strip is to give additional strength to the border wire and to give a broad supporting surface at that point of the spring where 40 one's legs hang over.

The ties are diagonally arranged coil springs which are not broadly new for this purpose, but it is thought that the combination of these coil springs and the floating 45 guide rod which passes through them and serves to automatically lock the tying springs to the supporting springs, is new. The coil springs are designated *g*; the guide rods *h*. Referring to Fig. 3, it will be apparent how very easily and nicely the ties 50 are connected with the top coils of the supporting springs. The coiled tie *g* is slipped over the top part of the spring, slightly spreading two of the coils of the tie. Where

two of the coiled ties intersect, they are 55 slipped down over each other by spreading the coils. The guide wire or rod *h* is then inserted, the result being that this in connection with the coils, as for instance, at *i* (Fig. 3) locks the top coil of the hour-glass 60 spring and the tie together, but at the same time allows the top coil of the hour-glass spring to move in a substantially horizontal plane along the guide rod *h*. A similar joint between intersecting coils or ties is detailed 65 in Fig. 4.

If a load is received at the middle of the cushion spring, the hour-glass springs, of course, tend to collapse, but the downward movement of the top coils is resisted by the 70 adjacent parts of the coil spring of the tie and more so by the guide rod *h*, which the load tends to flex, thereby placing a longitudinal pull on the guide rods, which is frictionally resisted by the contact of the coils 75 all along the length of the rod and by intersecting ties. At the ends of the rods they are preferably hooked over as at *j*, and where two hooks come together as at *k*, they are clipped together. The ends of the coil 80 springs abut against these hooks, and consequently when the guide rod is flexed under a load or one of the hour-glass springs through which it passes, the flexure pulls the rod and this pull of the rod is resisted 85 at the ends by the entire length of the coil springs. The consequence of this construction is that the load is distributed over the entire upper surface of the cushion, yet the top coils of the hour-glass springs 90 are not unnecessarily tipped over to tend to keep their erect position by reason of being held up by the guide rods. It is also to be noted that the guide rods in connection with the coil springs through which they pass, 95 lock the ties to the hour-glass springs and the intersecting ties without any further fastening; yet the lock is of such character that one may move with respect to the other—a very desirable feature in connection with the distribution of strains over the entire spring. This form of a tie also forms a strong support for the upholstering cover both in spaces intervening between the springs and also in the spaces described 100 by the top coils of the supporting springs.

It is not absolutely necessary that the ends of the ties be hooked and free, they

might be attached in various ways to a rim member or other device. This is indicated in the lower part of Fig. 1.

What we claim is:

- 5 1. In a cushion spring, the combination of a plurality of supporting springs, a tie therefor, comprising a coil spring fitting over the top coils of the supporting springs, and a rod passing through the coils of the
- 10 10 coil springs and serving in connection with the same to lock the tie to the top coils of the supporting springs and having one or more of its ends arranged to abut against the end or ends of the coil springs.
- 15 2. In a cushion spring, the combination of a plurality of supporting springs, a plu-

rality of intersecting ties, each tie including an extensible and contractible member provided with means for transmitting stresses to the ends of the tie where they are resisted by yielding resistance to the longitudinal contraction of the tie.

3. In a cushion spring, the combination of a plurality of coil springs, a border wire, and a flat strip secured to the border wire 25 along the front edge of the cushion spring and supported on top of the supporting springs, for the purpose specified.

In testimony whereof we sign this specification.

GUSTAV O. BRANDT.
THOMAS MAHONEY.
